US00D917409S

(12) **United States Design Patent** (10) Patent No.: **US D917,409 S**
(45) Date of Patent: **** Apr. 27, 2021**

(54) **MEDIA EXTENDER**

- (71) Applicant: **Amazon Technologies, Inc.**, Seattle, WA (US)
- (72) Inventors: **Matthew Michael Seflic**, San Jose, CA (US); **Christopher Green**, San Francisco, CA (US); **Marc Rene Walliser**, San Francisco, CA (US)
- (73) Assignee: **Amazon Technologies, Inc.**, Seattle, WA (US)
- (**) Term: **15 Years**
- (21) Appl. No.: **29/745,872**
- (22) Filed: **Aug. 10, 2020**

(57) **CLAIM**

The ornamental design for a media extender, as shown and described.

DESCRIPTION

FIG. 1 is a top, front, right-side perspective view of a first embodiment of a media extender;
FIG. 2 is a bottom, back, right-side perspective view thereof;
FIG. 3 is a front view thereof;
FIG. 4 is a back view thereof;
FIG. 5 is a left-side view thereof;
FIG. 6 is a right-side view thereof;
FIG. 7 is a top view thereof;
FIG. 8 is a bottom view thereof;
FIG. 9 is a top, front, right-side perspective view of a second embodiment of a media extender;
FIG. 10 is a bottom, back, right-side perspective view thereof;
FIG. 11 is a front view thereof;
FIG. 12 is a back view thereof;
FIG. 13 is a left-side view thereof;
FIG. 14 is a right-side view thereof;
FIG. 15 is a top view thereof; and,
FIG. 16 is a bottom view thereof.

The broken lines depict portions of the media extender that form no part of the claimed design.
